UNITED STATES PATENT OFFICE.

CHRISTIAN HEILRATH, OF SACRAMENTO, CALIFORNIA.

TONG-WRENCH.

1,205,346.

Specification of Letters Patent. Patented Nov. 21, 1916.

Application filed June 19, 1916. Serial No. 104,486.

To all whom it may concern:

Be it known that I, CHRISTIAN HEILRATH, a citizen of the United States, residing at Sacramento, in the county of Sacramento, 5 State of California, have invented certain new and useful Improvements in Tong-Wrenches; and I do declare the following to be a full, clear, and exact description of the same, reference being had to the accompanying drawings, and to the characters of reference marked thereon, which form a part of this application.

This invention relates to improvements in wrenches used for loosening and tightening 15 nuts of all kinds, the object of the invention being to produce a wrench consisting of a pair of tongs pivotally mounted at a point off the center of the axis of the wrench, such tongs terminating in jaws arranged to engage 20 the nuts in an immovable grip which, due to the peculiar pivoting together of the tongs, will tend to grow tighter as the wrench is turned to loosen or tighten the nut. One of the tongs of the wrench is movable 25 longitudinally with relation to the other so as to vary the space between the jaws for the purpose of fitting different sized nuts.

In making the statement that I aim to design a wrench which will fit all classes of 30 nuts, I make this without reservation inasmuch as my improved tong wrench will grip and firmly hold a nut having any number of flat sides, or a nut which is perfectly round on its sides, or in place of a nut a collet may 35 be placed over the nut and my wrench then used to engage the collet so that a square nut may be turned in a very limited space.

A further object of the invention is to produce a simple and inexpensive device and yet 40 one which will be exceedingly effective for the purposes for which it is designed.

These objects I accomplish by means of such structure and relative arrangement of parts as will fully appear by a perusal of 45 the following specification and claim.

In the drawings similar characters of reference indicate corresponding parts in the several views.

Figure 1 is a side elevation of my improved wrench. Fig. 2 is an edge view of 50 the same. Fig. 3 shows the jaws as they appear in engagement with a square sided nut. Fig. 4 is a view showing the jaws as they appear when engaged with a round nut or a 55 collet on a square nut. Fig. 5 is a detached view of a collet. Fig. 6 is a plan view of a

modified form of the wrench showing the jaws in the reverse position to that shown in Fig. 1.

Referring now more particularly to the characters of reference on the drawings, I first provide a carrier 1 which is provided with a recess 2 turnable within which recess is an actuating worm 3 of the type usual in wrenches. At one end of the carrier 1 is 60 a pair of projecting ears 4 pivotally mounted between which as at 5 is one of the tongs 6, such tong 6 being guided between projecting guides 7 at the opposite end of the carrier 1, the bottom of said guides limiting the 65 movement of the tong 6 toward the other tong 8 which is movable longitudinally through the carrier 1. This tong 8 is provided with a plurality of teeth 9 along its inner edge to be engaged by the worm 3 for 70 advancing the tong 8 longitudinally through the carrier 1. 75

The outer end of the tong 6 terminates in a serrated jaw 10 while the tong 8 terminates in a serrated end 11 arranged substantially 80 parallel with respect to the inner edge of the jaw 10, such end 11 in turn terminating in the projecting finger member 12 for a purpose as will appear.

The tong 8 is advanced through the carrier 1 to separate the jaws 10 and 11—12 to fit different sized nuts and also the pivotal relation of the tong 6 with respect to the tong 8 aids in this same function.

The jaws 10 and 11—12 being engaged 90 with the nut, the wrench is turned, which brings the faces of the jaws 10 and 11 into a frictional grip with the nut, and the more there is a tendency to turn the wrench the tighter this grip will become due to the pivoting of the parts as at 5 off center of the axial alinement of the nut. 95

The projecting finger member 12 greatly aids in the gripping of the nut for the reason that it engages a side thereof at a substantial angle to the surface 11 which engagement tends to increase as the nut is rotated. This action prevents the wrench from readily slipping off the nut while in engagement therewith.

While my wrench is extremely advantageous in conjunction with square sided nuts, still one of the most important features of its use is that wherein it can be used with round nuts. When square sided nuts are used and there is limited space in which to move same for tightening or loosening, a

socket 13 as shown in Fig. 5 which has a round periphery can be used. My improved wrench can then be used on the socket 13 and due to its round periphery, a very limited movement may be had and at the same time loosen or tighten the nut 14 which may be within this socket. As a matter of fact the socket 13 would be used in combination with my improved wrench and when so used, my improved wrench would become practically a socket wrench having a removable socket or collet and I make this claim especially for my wrench.

In Fig. 6 I show a modified form of wrench in which the jaws are in relatively reverse position to that shown in Fig. 1. In this view 1^a designates the carrier, 6^a the pivoted tong, 8^a the longitudinally movable tong, and 3^a the advancing worm. It will be noted that the jaws 10^a and 11^a are the reverse to the jaws 10 and 11, and the tong 8^a moves relatively the reverse of the tong 8. This structure may sometimes be found advantageous, hence I make a showing of same here.

My improved wrench is not only adaptable for the removing of nuts, but can be used for the moving of round objects such

as screws, pipes, or any other similar objects which are threaded in another part and 30 which it might be desired to be moved.

From the foregoing description it will be readily seen that I have produced such a device as substantially fulfills the object of the invention as set forth herein. 35

While this specification sets forth in detail the present and preferred construction of the device, still in practice such deviations from such detail may be resorted to as do not form a departure from the spirit of the invention as defined by the appended claim. 40

Having thus described my invention what I claim as new and useful and desire to secure by Letters Patent:

A tong wrench comprising a carrier provided with a recess and a longitudinal slot opening into the recess, a tong movable through the slot and provided with teeth along its edge projecting into the recess, a worm turnably mounted in the recess and 50 engaging said teeth, and another tong pivoted to the carrier at a point off center of the axis of the first named tong, said tongs having coacting jaws.

In testimony whereof I affix my signature. 55
CHRISTIAN HEILRATH.
